CLAIM

The ornamental design for a tile blade for electric saw, as shown and described.

DESCRIPTION

FIG. 1 is a perspective view of a first embodiment of a tile blade for electric saw showing our new design in a position of use with environmental subject matter;

FIG. 2 is a perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the tile blade for electric saw of FIG. 1 shown in a position of use with environmental subject matter.

FIG. 10 is a front elevational view of a second embodiment of a tile blade for electric saw; and,

FIG. 11 is a front elevational view of a third embodiment of a tile blade for electric saw.

The broken lines shown in FIGS. 1 and 9 depict environmental subject matter that forms no part of the claimed design.
